Term of patent 7 years

Int. Cl. D18—01

U.S. Cl. D26—5 C

FIG. 1

FIG. 2

FIG. 3

FIG. 1 is a top plan view of a thermal printer showing our new design.

FIG. 2 is an end elevational view thereof.

FIG. 3 is a side elevational view thereof.

The side of the terminal printer which is not shown is substantially a mirror image of the side which is shown in FIG. 3. Areas indicated by the numerals 10, 11 and 12 are of contrasting colors and materials relative to all other surfaces. The areas 11 and 12 are of the same color.

We claim:

The ornamental design for a thermal printer, as shown and described.
